UNITED STATES PATENT OFFICE.

HENRY BARDSLEY, OF PROVIDENCE, RHODE ISLAND.

SHUTTLE-BOX-OPERATING MECHANISM FOR LOOMS.

SPECIFICATION forming part of Letters Patent No. 681,648, dated August 27, 1901.

Application filed April 15, 1901. Serial No. 55,800. (No model.)

To all whom it may concern:

Be it known that I, HENRY BARDSLEY, a citizen of the United States, residing at Providence, in the county of Providence, State of Rhode Island, have invented a certain new and useful Improvement in Shuttle-Box-Operating Mechanisms for Looms, of which the following is a specification, reference being had therein to the accompanying drawings.

- 10 The invention has relation more especially to shuttle-box-operating mechanism of that class in which an intermittently-operated driver or master gear or wheel partially rotated step by step is employed for the purpose of actuating under the control of pattern devices the train or trains of operating and transmitting connections through which the box-lever is moved to shift the shuttle-boxes and in which a train such as has just 15 been referred to comprises a partially toothed or mutilated pinion which at times is engaged and given a semirevolution by the said driver or master gear or wheel, a crank or eccentric rotating in unison with said pinion, 20 and operative connections from said crank or eccentric to the box-lever.

At the customary high rate of speed at which looms are run considerable shock and strain result when the master gear or wheel after 25 each partial movement thereof is brought suddenly to a state of rest. One object of the invention is to reduce this shock and strain. One part of my invention consists, accordingly, in a construction and combination of gear-segments for operating the master-wheel by means of which the master gear or wheel is started at its maximum rate of speed and is gradually decreased in speed to the end of its partial movement.

- 30 In my prior United States Letters Patent, No. 626,960, granted June 13, 1899, I have presented an improved form of shuttle-box motions or operating mechanism in which each partially toothed or mutilated pinion is 35 furnished with a diametrical lever mounted to turn in unison with the said pinion and to swing in the direction of the axis of the pinion, the position of the diametrical lever being determined by pattern devices, whereby 40 the engagement of the respective ends of the said lever with the starting-teeth of the master-gear is controlled. In the said patent the

locking of the pinion to prevent overrunning thereof or accidental untimely movement of rotation is effected by means of a spring-actuated locking-lever held pressed by its spring against the periphery of a collar carried by the pinion, the said collar having opposite locking-notches which are entered by the said lever on the completion of the semirevolutions of the pinion.

One object of my present invention is to provide in improved manner for locking the pinion whereby the friction and resistance to the rotation of the pinion, tendency to wear, failure to act, and lack of positiveness of the locking action are obviated, a positive and certain locking action being secured.

Another object of the invention is to provide in improved manner for throwing the shuttle-box-operating mechanism out of driving connection with the rotating shafts of the loom instantly upon the action of the weft-detector mechanism of the loom.

In the operation of shifting shuttle-boxes containing more than four cells difficulty is experienced on account of the failure of the bottoms of certain cells of the series to line up horizontally with the shuttle-race of the lay. This difficulty is not experienced to any inconvenient extent up to, say, the fourth cell of a series, but when lifting the shuttle-boxes to bring, say, the fifth or the sixth cell of the series into position the want of alinement is noticeable and objectionable. One object of my invention is to obviate this drawback by providing means for making compensation therefor.

The invention consists in various improvements by means of which the foregoing objects are attained and which will now be described with reference to the accompanying drawings, in which latter I have shown a convenient embodiment of the various features of the invention.

In the drawings, Figure 1 shows in side elevation a portion of one side frame of a loom having the said embodiment of the invention applied thereto. Fig. 2 shows in rear elevation the parts which are represented in Fig. 1. Fig. 3 is a view showing chiefly a plan of the compound box-lever. Figs. 4, 5, and 6 show from different points of view one of the partially toothed or mutilated pinions and its ad-

junctions. Fig. 7 is a sectional view of one of said pinions. Fig. 8 is a detail view of the stop-motion connections on a reduced scale. Fig. 9 shows in rear elevation certain portions of the driving and stop-motion arrangements. Fig. 10 is a detail view of certain of the rotating parts looking from the left in Fig. 9.

Having reference to the drawings, 1 designates a portion of the frame of a loom.

2 is one of the rotating shafts of a loom. This shaft in the present embodiment of the invention has fixed thereon the driver, forming one member of the gearing-train by which the master-gear is rotated intermittently part 5 of a revolution. The said driver comprises, essentially, a gear-segment 3. The member of said gearing-train with which driver 3 engages comprises, essentially, a gear 4, which in the present embodiment of the invention 10 is coaxial with the master gear or wheel 5, the driven gear 4 and master gear or wheel being connected with each other to rotate in unison. Driven gear 4 is provided with a number of gear-segments intended to be engaged successively by the driver-segment 3 15 and has gaps or spaces intermediate said segments at which the driver-segment 3 runs out of mesh with one of the said gear-segments after having communicated a movement of the required extent to the driven gear 4 and master-gear 5. Driver 3 is furnished with a locking-flange or "rest" 3^a at one side of its hub 3^b, extending around that portion of the circumference of the said hub which is not 20 occupied by the teeth of the segment, and the driven segmental gear 4 is furnished at each gap or space between two of its segments with a pair of projections 4^a 4^b to coöperate with the said locking-flange or rest in holding the segmental gear 4 and master-gear 5 from overrunning and from accidental movement after the 25 driver-segment 3 has run out of mesh with one of the segments of the said driven gear 4 and while the latter and the master-gear should stand at rest. Driver-segment 3 also 30 has the starting-teeth 3^c 3^d at the opposite ends of the same for engagement in customary fashion with the starting-teeth 4^b 4^c, &c., of the segmental gear 4. For the purpose of 35 transmitting to the master gear or wheel 5 a speed gradually decreasing from start to finish the pitch-line of the gear-segment 3 is curved inward toward the axis of rotation of the driver 3 from the first tooth of said 40 driver to the last, while each segment 4^e of the driven segmental gear 4 has the pitch-line thereof reversely curved—that is, outwardly from the axis of rotation of the said segmental gear. For the purposes of this 45 case the idea of the relation of the pitch-lines of the segments to the respective axes of rotation may be expressed by saying that the gear-segments of the driver and driven wheel are eccentrically disposed for the purpose of transmitting motion at a progressively-decreasing rate of speed to the master gear or wheel at each advance of the latter.

The master-gear 5 is provided, as usual, with a number of toothed segments 5^a 5^b for the actuation of the partially toothed or mutilated pinions, with starting-teeth 5^b 5^c, &c., at the ends of such segments for engagement with the diametrical levers of the said pinions and with intermediate plain surfaces or rests 5^c 5^d for holding the said pinions from rotation between times. The said pinions are indicated at 6 6 6. Each of said pinions has connected therewith a crank, as 6^a, which is connected by means of a link or connecting-rod, as 6^b, with the box-lever. The number of pinions employed and the character and arrangement of the box-lever will vary according to the number of cells contained in the series of shuttle-boxes. The said cells may vary in number in different cases in practice, as required. The present embodiment of the invention has been designed for operating a series of shuttle-boxes containing six cells. Accordingly there are three pinions, and the box-lever is a compound lever comprising two simple levers. What for the purposes of this case may be termed the "main" lever 7 of the compound box-lever has pivoted to its forward arm the link 8, extending upward and connected pivotally with 90 the box-rod 8^a. The said main lever 7 is pivoted upon the forward extremity of the secondary lever 7^a. The latter has connected therewith two of the connecting-rods 6^b 6^b, one at the rear extremity thereof and one at 95 an intermediate point, while the main lever 7 has one connecting-rod 6^b, connected therewith at its rear extremity. The action of the cranks in operating the compound box-lever is well understood by those skilled in the 100 art. For the purpose of steadyng the compound box-lever in the movements thereof the rear extremity of the main lever 7 has pivoted thereto the rear extremity of the radius-arm 9, the forward extremity of which 105 is connected pivotally with the loom-frame, as at 9^a, Fig. 3.

The diametrical lever with which in the present embodiment of the invention each pinion is provided (see more especially Figs. 115 4, 5, 6, and 7) is designated 10. The actuating-spindle of said lever is shown at 10^a and the fingers thereon for engaging with the lever at 10^b 10^c, while the spring which acts on said rod to move it endwise in one direction is designated 10^d.

11 11^a 11^b designate levers or fingers forming part of pattern connections whereby to determine the engagement of the respective diametrical levers with the starting-teeth on 125 the master gear or wheel. These levers or fingers are connected with and operated from the devices which are employed in connection with the pattern-chain or other pattern-surface. These levers or fingers are herein for 130 convenience shown arranged and operated as follows: The finger 11 is fast on rock-shaft 12, the latter having an arm 12^a. Finger or lever 11^a is loose on rock-shaft 12. Finger

11^b is fast on rock-shaft 12^b, the latter having an arm 12^c. Arms 12^a 12^d and finger or lever 11^a are joined by connections 13 13 13 with the pattern devices aforesaid, which last are 5 of any preferred or known character and are not necessary to be shown. Pattern fingers or levers 11 11^a 11^b when operated through the agency of the pattern devices act to move spindles 10^a and diametrical or starting lever 10 in one direction in opposition to the action of the springs 10^d, while the reverse movements of the spindles and levers are occasioned by the said springs when the pattern devices permit these last to act. While the 15 pinions are at rest, the diametrical or starting levers stand radially with reference to the master gear or wheel, but with the inwardly-turned arms or teeth thereof swung laterally out of the plane of rotation of the starting- 20 teeth on the said master gear or wheel, so as to be out of the range of action of the said starting-teeth. When, however, the pattern devices operate to cause the lever of a given pinion to be swung so as to carry its inwardly- 25 extending arm laterally into the plane in which the starting-teeth of the master gear or wheel rotate, a rotary movement of the said pinion is occasioned. At the end of a semirevolution of the pinion the latter is left 30 at rest. For the purpose of locking positively the pinion in its new position as well as preventing overrunning of the pinion I place a flange 14 adjacent each pinion in position to project across the plane of rotation 35 of one of the arms of the laterally-swinging diametrical or starting lever. This flange preferably is curved concentrically with the pinion and preferably also, though not invariably, is located adjacent the outer portion 40 of the pinion in position to coact with the arm last engaged by a starting-tooth of the master gear or wheel. Its end portions 14^a 14^b are beveled off to facilitate movement of the diametrical lever onto such end portions. The 45 said flange is furnished with a notch 14^b, into which the coacting arm of the lever passes at the completion of the semirevolution of the pinion. The diametrical lever remains in the notch 14^b until the pattern devices operate to press the arm thereof which now extends inwardly laterally into the plane of rotation of the starting-teeth of the master gear or wheel. The lateral movement of the said lever thus occasioned through the operation 50 of the pattern devices withdraws the lever from the notch 14^b of the stop-flange prior to the engagement of the inwardly-extending arm of the lever by one of the starting-teeth of the master gear or wheel. 55 For the purpose of rendering the shuttle-box operating mechanism inoperative through the action of the weft-indicator mechanism I combine the said weft-indicator mechanism with the starting-teeth of one of the 60 segmental wheels of the driving-train for the master gear or wheel in such manner as to withdraw the said starting-teeth from opera-

tive position. This makes a break in the said driving-train and leaves the master gear or wheel at rest until the withdrawn starting-teeth are reinstated in working relations again. I have herein shown the starting-teeth 4^b 4^b of the segmental driven gear 4 arranged to be withdrawn and reinstated as aforesaid, and in this particular embodiment of the invention I have arranged the said teeth 4^b 4^b to be shifted laterally out of the plane of rotation of the starting-teeth 3^c 3^c of the driver-segment 3 and back again into the said plane. The said starting-teeth 4^b 4^b of the gear 4 are 70 in this instance carried by a disk 4^d at one side of the gear 4, the said disk being provided with opposite pins 4^e 4^e, working within holes formed through the body of gear 4 parallel with the axis of rotation of the gear and disk. 75 Thereby the disk and gear are caused to rotate in unison with capacity for relative movement transversely. The master-gear 5 and segmental gear 4 are fast upon opposite ends of a sleeve 4^f, into the interior of which last extends the headed bolt 4^g, having the threaded end thereof screwed into the center of the disk 4^d. A spiral spring 4^h, surrounding the stem of the bolt and compressed between the head of said bolt and a shoulder which is 80 provided at the inner end of the chamber of the said sleeve, acts to hold the disk 4^d in normal working position. The hub of disk 4^d has a groove, in which is engaged the fork of a shifter 4ⁱ, mounted on rock-shaft 4^k, the latter having an arm 4^m connected by a link 4ⁿ, Fig. 8, with an arm 4° on a rock-shaft 4^r, the latter having an arm 4^s projecting into the path of the weft-fork slide 4^t. When the said slide is moved forward in the loom in 85 consequence of engagement of the gooseneck 4^p with the weft-fork 4^q, as in the event of absence of the weft-thread from in front of the weft-fork at the time of the beat-up of the lay, the shifter 4ⁱ will be operated to withdraw the starting-teeth 4^b 4^b into inoperative 90 position.

When employing a shifting shuttle-box mechanism having cells for more than four shuttles—as, for example, in a six-cell-box motion—the bottoms of the upper four cells may without great difficulty be caused to aline themselves satisfactorily with the shuttle-race of the lay. With the fifth and sixth cells, however, the lack of horizontal alinement is sufficiently great to be noticeable and undesirable. The reason for this is the fact that as the shuttle-boxes rise to their highest positions the upward and rearward curvilinear movement of the forward extremity of 105 the main shuttle-box lever 7 straightens out the angle between said lever and the link 8 to a sufficient extent to give a noticeable excess of upward movement to the series of shuttle-boxes. With the object in view of rendering all of the vertical step-by-step movements of the shuttle-boxes equal in extent instead of slightly greater progressively in proportion as the boxes rise I employ compensating 110

means which I will now proceed to describe. (See Figs. 1 and 3.) The forward extremity of the secondary lever 7^a has a transverse eye 7^b , in which is received the pin 7^c . The eye 7^d of the main lever 7 receives a sleeve 7^e , having an eccentrically-disposed bore, which receives a portion of the length of the pin 7^c , the pin and sleeve being locked together to turn in unison, as by means of a key 7^f . To one end of sleeve 7^e is made fast the lever 7^g , the latter having an arm 7^h , which is connected by means of a contracting spiral spring 7^i with a rear portion of main lever 7 , whereby a stop 7^k , forming part of said lever 7^g , is held in contact with a portion of said main lever. It will be perceived that the pin 7^c and sleeve 7^e (which may be formed in one piece, if required) constitute an eccentric connection between the main lever 7 and secondary lever 7^a . At 7^m is shown a fixed stop, which is located in position to be encountered by the forwardly-projecting arm of the lever 7^g . When the said arm encounters the said stop during the rise of the forward portion of the compound shuttle-box lever, the arm is held back through a portion of the said rise, with the result that a slight movement of main lever 7 relative to secondary lever 7^a occurs sufficient in extent to offset the gain due to the cause already explained. For the purpose of enabling the stop 7^m to be adjusted into proper position it is applied to a stand 7^n , the latter having a horizontal slot 7° , through which passes a bolt 7^p , by which the said stand is attached to the loom side. The said slot enables the stand and stop to be adjusted in the direction of the length of the lever 7^g . Vertical adjustment of the stop is provided for by means of a set-screw 7^q , passing upward through a lug of the stand 7^m and taking bearing against the under side of a flange 7^s of the loom side, the said set-screw being furnished with a check-nut 7^t .

What I claim is—

- 45 1. In a loom, in combination, the master gear or wheel, shuttle-box-operating mechanism operated therefrom, and means for moving said master gear or wheel intermittently with decreasing speed from start to finish of each movement, substantially as described.
- 50 2. In a loom, in combination, the master gear or wheel, shuttle-box-operating mechanism operated therefrom, a segmental driven gear connected operatively with the said master gear or wheel, and a rotating driver-segment, with the gear-segments of the driver and driven gear eccentrically disposed to transmit motion at a progressively-decreasing rate of speed to the master gear or wheel at each advance of the latter, substantially as described.
- 55 3. In combination, the master gear or wheel, the partially toothed or mutilated pinion, its diametrical lever, pattern devices controlling said lever, and the flange adjacent said pinion having the notch which receives the said lever to lock the pinion, substantially as described.

4. In combination, the master gear or wheel, the partially toothed or mutilated pinion, its diametrical lever, the spring and pattern devices acting in connection with the said lever, and the flange adjacent said pinion having the notch which receives the said lever to lock the pinion, substantially as described. 75

5. In a shuttle-box-operating mechanism for looms, in combination, the master gear or wheel, a driving-train operating said gear or wheel intermittently and including a segmental wheel having starting-teeth, and stop-motion devices having operative connection with said starting-teeth to withdraw the latter from their operative position when said devices act, substantially as described. 80

6. In a shuttle-box-operating mechanism 85 for looms, in combination, the master gear or wheel, a driving-train operating said gear or wheel intermittently and including a segmental wheel having starting-teeth which are movable laterally from their operative position into inoperative position, and stop-motion devices having operative connection with said starting-teeth to shift the latter into inoperative position when said devices act, substantially as described. 90

7. In a shuttle-box-operating mechanism for looms, in combination, the master gear or wheel, a segmental gear in operative connection therewith and having a laterally-movable series of starting-teeth, a driver-segment 100 acting in connection with said segmental gear, and stop-motion devices having operative connection with said starting-teeth to withdraw the latter into inoperative position when said devices act, substantially as described. 105

8. In a shuttle-box-operating mechanism for looms, in combination, the master gear or wheel, a segmental gear in operative connection therewith and having a laterally-movable disk carrying a series of starting-teeth, a 110 spring to hold said disk with the said teeth in operative position, a driver-segment acting in connection with said segmental gear and stop-motion devices having operative connection with said disk to withdraw the latter and its teeth laterally to place said teeth in inoperative position, substantially as described. 115

9. In a shuttle-box-operating mechanism for looms, in combination, the master gear or wheel, an intermittent gear-driving train therefor, stop-motion devices, and means connected with said devices whereby the latter act to disestablish working relations between an intermittently-rotated driven member of 120 said train and the driving member therefor. 125

10. In a shuttle-box-operating mechanism for looms, in combination, the box-lever, box connections therefor, operating means for said box-lever, and a compensating device 130 to equalize the various shifts of the series of shuttle-boxes, substantially as described.

11. In a shuttle-box-operating mechanism for looms, in combination, the box-lever, box

connections therefor, operating means for said box-lever, and a compensating device co-acting with said box-lever to equalize the shifts of the series of shuttle-boxes, substantially as described.

12. In a shuttle-box-operating mechanism for looms, in combination, the compound box-lever, box connections therefor, operating means for said box-lever, and a compensating device interposed between the simple levers forming said compound box-lever, to equalize the shifts of the series of shuttle-boxes, substantially as described.

13. In a shuttle-box-operating mechanism for looms, in combination, the box-lever, box connections therefor, operating means for said box-lever, and a compensating device having one member thereof combined with the box-lever and another member applied to a relatively-fixed support, to act during the shifting of the shuttle-boxes to equalize the various shifts of the series, substantially as described.

14. In a shuttle-box-operating mechanism for looms, in combination, the box-lever, box connections therefor, operating means for said box-lever, and a compensating device comprising an eccentric member movable in connection with the box-lever and a second member applied to a relatively-fixed support to act in connection with said eccentric mem-

ber during the shifting of the shuttle-boxes to equalize the various shifts of the series, substantially as described.

15. In a shuttle-box-operating mechanism for looms, in combination, the compound box-lever, box connections therefor, operating means for said box-lever, and a compensating device having an eccentric member interposed between the simple levers constituting the compound box-lever, and a coacting member applied to a relatively-fixed support, to act during the shifting of the shuttle-boxes to equalize the various shifts of the series, substantially as described. 35

16. In a shuttle-box-operating mechanism for looms, in combination, the compound box-lever, box connections therefor, operating means for said box-lever, and the compensating device having the eccentric member interposed between the simple levers constituting the compound box-lever, and the fixed stop, whereby the various shifts of the series of shuttle-boxes are equalized, substantially as described. 40 45

In testimony whereof I affix my signature in presence of two witnesses.

HENRY BARDSLEY.
